OHIO

LOOSE-LEAF BINDER

Application filed September 20, 1928. Serial No. 307,194.

This invention relates to an improved loose leaf holder or binder and is especially adapted for service in hospitals or the like, for the purpose of holding and protecting the 5 loose leaf sheets upon which clinic or other records or memoranda are maintained. These records are constantly employed in active cases and are subject to considerable handling by those noting the progress of each individual case, and since these records are kept on paper sheets, it is necessary that an efficient holder or binder be provided therefor to protect the sheets from defacement, mutilation or other damage or impairment affecting their usefulness.

The holder or binder comprising the present invention provides means for meeting the above requirements and consists broadly of a pair of flexibly connected covers or binding members, between which the record sheets are removably positioned. The back cover is provided with outwardly projecting pins or studs which extend through perforations in the upper edges of the record sheets to fix 25 the retained positions of the sheets between the covers, and in addition to this, the front cover includes a spring actuated clamping or gripping member, which is so constructed and arranged, that when the covers are 30 brought into closed relation, the gripping member, through spring pressure will be forced into and maintained in clamping engagement with the record sheets or leaves, securely holding the latter between the covers. The front cover further includes a flap 35 which is hinged to the gripping member, but so mounted as to be independent of the clamping action of the gripping member, whereby the record sheets may be readily viewed without disturbing their fixed positions within the holder.

The foremost object of the invention is the provision of a holder of the above nature wherein an improved structure or spring arrangement is presented for the purpose of controlling the clamping action of the gripping member on the sheets. This arrangement is such that while a positive and secure grip is imparted to the sheets by the gripping member, yet the latter by simple and easily

effected manual operation, may be moved from active to inactive clamping positions without difficulty, noise, or other objection of a like nature which so strongly characterize the operations of previous holders designed 55 for this service.

Other general objects consist in the provision of a durable, simple, economical and efficient holder of the character set forth, designed to impart extended service, easy and 60 simple to operate, and practically free of the liability of mechanical disorder.

In the accompanying drawings, forming a part of this specification and in which similar characters of reference denote like and 65 corresponding parts throughout the several views thereof:

Figure 1 is a perspective view of the improved holder or loose leaf binder comprising the preferred form of the present invention. 70

Figure 2 is a perspective view of the binder showing the covers thereof in an open position.

Figure 3 is a vertical sectional view taken through the clamping end of the binder and 75 showing the gripping member in its clamping position, and

Figure 4 is a similar view showing the gripping member in an open or releasing position.

Referring more particularly to the details 80 of the specific form of the invention illustrated in the accompanying drawings, the numeral 1 designates the improved binder in its entirety. In this form of the invention the binder is formed to include a relatively 85 fixed back-cover or member 2, and a movable front-cover 3. These covers are preferably formed from sheet metal and may be of any suitable size and proportion to accord to the size of the individually removable record 90 sheets 4 which are adapted to be held within the binder between its covers. The back cover 2 has one end thereof bent to provide an angularly extending flange 5, to the outer end of which is hinged as at 6, a gripping or 95 clamping member 7, forming a part of the front cover structure 3. This member consists of a flanged portion 8 which terminates in an angularly bent downwardly extending web 9, and the lower edge of this web is 100

adapted to be forced by spring pressure into and out of clamping engagement with the record sheets 4. To the lower edge of the web there is hinged as at 10 a flap or cover 11, 5 also constituting a part of the front cover structure. The flap is free to move about its hinge connection 10 with the gripping member 7, in order that access to the record sheets may be readily obtained without interfering 10 with the retention of said sheets in the binder. The flap serves to completely protect the record sheets, even when the binder is roughly handled; to guard the sheets against wear and tear and to insure privacy as to the matter provided upon the records. The sheets are further retained within the binder by providing the back cover with a pair of fixed pins or studs 12, which project forwardly and are adapted to pass through perforations 13 provided in the upper ends of said record 20 sheets and also through registering perforations 14 formed in the gripping member.

One of the essential features of the present invention consists in the provision of an improved spring arrangement for controlling the spring action of the gripping member. In prior devices of this kind considerable difficulty has been experienced in opening or closing the covers to control the insertion or 30 removal of record sheets with respect to the binder. The principal objection in a mechanical way to these prior structures, has consisted in the faulty spring construction, which has been both difficult and tedious to 35 operate and wears out quickly after but relatively short periods of use. To obviate this the present invention provides a strip of resilient material 15, which is secured to the back cover 2 in a fixed position by rivets 16 40 so as to extend in spaced relation from and parallel to the flange 5. The gripping member is formed with a plurality of offset, and in this instance integral lips 17, which project downwardly and inwardly from the upper edge of the gripping member adjacent to 45 the hinge connection 6. The free edges of these lips are rolled or rounded, as at 18, to engage with similarly rolled or rounded portions 19 provided upon the strip 15 and disposed midway between the spaced rivets 16. These parts are proportioned and arranged 50 so that when the gripping member is oscillated to assume a closed or clamping position, the resilient member 15 will be flexed until after the free ends of the lips 18 have 55 passed beyond the rounded portions 19 of said strip, whereupon the pressure on the spring strip is somewhat relieved and the spring is allowed to return to its normal position, pressing strongly and firmly on the offset or crank-like lips 17, in such manner as 60 to force the lower gripping edge of the member 7 into firm and positive engagement with the record sheets in the binder. The corresponding action takes place when the grip-

ping member is moved to assume the open position set forth in Figure 4. By rounding the meeting edges of the lips 17, and the spring strip 15 I secure a firm and positive operation, but one which may be effected with 70 but a minimum of mechanical difficulty. In this connection it will be observed that the flap portion of the front cover may be used as a lever to assist the operator in moving the gripping member against the resistance 75 offered by the spring strip 15. Another feature resides in extending the strip 15 beyond the vertical side edges of the back cover 2, so as to produce horizontal extensions or trunnions, which are used in supporting the 80 binder upon any suitable rack or other holder. The gripping member is also provided along its front surface, between the outwardly projecting pins 12, with a name plate 20'.

It will be observed that the construction shown and described in detail is essentially simple, effective in operation and yet has the advantage of being very convenient and easy to operate. While I have described what I 90 consider to be the preferred form of my invention, nevertheless it will be understood that the specific details shown are of course subject to slight modification or variation and that such changes may be made in the 95 structure of the binder without departing from the spirit of the invention as expressed in the following claims.

What is claimed is:

1. In a loose leaf binder, a back member 100 having a forwardly projecting flange along one edge thereof, said flange occupying a plane substantially at right-angles to the main body of the back member, a gripping member having its upper edge 105 formed to provide an angularly extending flange, a hinge connection between the flanges of said back and gripping members, a spring structure for maintaining the free edge of said gripping member in yieldable engagement with said back member consisting of a leaf spring fixed to said back member and having a reinforced outer edge portion, and an inwardly offset lip projecting from the flange of said gripping member and arranged to impart stress to said leaf spring by cooperation with the reinforced edge portion of said spring when said gripping member is moved to assume a clamping position with relation to said back 115 member.

2. In a loose leaf binder, a back member formed with a forwardly projecting flange along the upper edge thereof, the outer edge of said flange being terminated in eyes constituting a portion of a hinge, a gripping member of substantially the same width as the said back member, said gripping member being provided with a flange terminating along one edge thereof in a plurality of 125 130

5 eyes arranged for complementary registration with the eyes of said first-named flange to provide a hinge connection between the back and gripping members, a hinged pintle within said eyes, rigid posts carried by said back member and extending perpendicularly from the latter, said gripping member being provided with openings adapted to receive said posts, a strip extending parallel with the 10 flange of said back member and spaced from the latter, a mounting for said strip for rigidly connecting the latter to said back member and admitting of the flexing of one edge of said strip, angularly disposed tongues 15 formed with said gripping member and arranged to cooperate with the free edge of said strip to retain said gripping member in and out of clamping engagement with the back member, and a cover plate hinged to the 20 lower edge of said gripping member.

3. In a loose leaf binder, a back member consisting of a flat sheet of rigid material, with a flange formed on its upper edge and projecting forwardly from the latter at substantially right-angles to the general plane thereof, the forward edge of said flange being provided with eyes, a hinge pintle within said eyes, a gripping member formed from a rigid plate-like material and having the upper portion thereof provided with an angularly bent flange formed with eyes arranged in complementary relationship with the eyes of said first-named flange for the reception of the hinge pintle, said gripping member being movable relatively to the back member to admit of the clamping of removable sheets of material therebetween, a metallic strip extending parallel with and immediately adjacent to the flange along the upper edge of 35 said back member, connections between one edge of said strip and said back member admitting of the flexing of the outer longitudinal edge of said strip, and a plurality of tongues formed with said gripping member 40 and projecting inwardly from the latter for swinging movement in unison therewith, the outer ends of said tongues being terminated for frictional engagement with the unsupported outer edge of said strip whereby the 45 latter operates to exert spring pressure on said tongues to positively retain said gripping member in and out of clamping engagement with the back member.

4. In a loose leaf binder, a back member, a gripping member hinged at one end to said back member, a metallic strip having spaced supports connecting said strip with the back member, the portion of said strip lying between said supports being resiliently movable, outwardly disposed tongues projecting from the gripping member for engagement with the resilient portion of said strip to retain said gripping member in and out of engagement with the back member.

5. In a loose leaf binder, a back member,

a gripping member hinged at one end to said back member, a metallic strip carried by said back member near the hinged end thereof and positioned at a right-angle thereto, said strip being free at one edge and mounted to flex to either side of its right-angular position with respect to the back member, outwardly disposed tongues projecting from the hinged end of said gripping member and adapted to engage with the free edge portion of said strip, said strip and tongues serving to retain said gripping member in and out of engagement with the back member.

6. In a loose leaf binder, a back member, a gripping member hinged at one end to said back member, an elongated metallic strip carried by said back member and having its outer free edge portion arranged parallel to the hinge between said members, a tongue carried by said gripping member and projecting inwardly so as to engage with the outer free edge of said strip, so as to impart stress to said gripping when it is moved to assume a clamping position with relation to said back member.

In testimony whereof, I have signed my name to this specification.

ISIAH CONRAD.
